UNITED STATES PATENT OFFICE

HORACE G. JOHNSON, OF KENOSHA, WISCONSIN, ASSIGNOR OF ONE-HALF TO HENRY S. COOPER, OF KENOSHA, WISCONSIN.

BIFURCATED UNDERGARMENT.

1,281,019.

Specification of Letters Patent.

Patented Oct. 8, 1918.

Application filed June 21, 1911. Serial No. 634,396.

To all whom it may concern:

Be it known that I, HORACE G. JOHNSON, a citizen of the United States, residing at Kenosha, in the county of Kenosha and 5 State of Wisconsin, have invented certain new and useful Improvements in Bifurcated Undergarments, of which the following is a specification.

This invention relates to that class of 10 underwear known as union suits, and has for its chief object to provide an improved construction of such garments permitting the use of a permanently closed crotch and providing ample width in the hip and thigh 15 regions and also providing a posterior opening large enough to be practical and simple to manipulate, and a closing means for said opening capable of making a complete and perfect closure without the use of a button, 20 loop, or like fastening at the waist-line or in the vicinity of the crotch; the opening being substantially self-closing.

A permanently closed crotch is a desirable 25 feature in union garments; but it has heretofore usually been employed in association with a relatively wide flap or drop-fall to cover the posterior opening, which flap or drop-fall has generally required several fastenings near the waist-line, and is 30 inconvenient to manipulate.

The chief aims and purposes sought in the present invention have been to provide an 35 improved garment of this character, which, while preserving the closed crotch feature, will also dispense entirely with the necessity of any detachable fastening whatever at the waist-line or in the vicinity of the crotch, and also to provide a garment having, in addition to the above-mentioned advantages, 40 the further features of greater ease and freedom in the use of the posterior opening; ample fullness in the hip and thigh regions, and perfect protection of the person of the wearer against exposure resulting from gap- 45 ing.

These objects I attain by a novel construction characterized chiefly by the provision of a seat-piece insertion of such form as to constitute a cover or closure of a posterior opening that extends from a point above the seat to a point downwardly below the crotch, and which has its lower angles formed into thigh-gore extensions, in combination with a flap extension which laps the free edge of the said seat-piece in-

sition and at its lower end by preference extends downwardly to the inner side of one or both legs forming a leg gore or gores, in which form the lower part or parts supplement the size of the closed thigh portion of the leg or legs, while the major portion of said flap extension supplements the size of the garment around the hips. 60

My invention, in two slightly differing forms is illustrated in the accompanying 65 drawings, in which—

Figures 1 and 2 are, respectively, front and rear elevations, broken off at the arms and legs, of one form of my improved garment, showing the same substantially as it 70 would appear on the human figure. Fig. 3 is a fragmentary plan view in detail of the crotch and adjacent portions of the garment, viewed from the inner side of the latter, as the same would appear were the 75 garment split longitudinally on each side and the front and rear halves of the upper or body portion spread out in a common plane with the inner sides of the leg portions extending at right-angles thereto. 80 Figs. 4 and 5 are views corresponding with Figs. 2 and 3, respectively, and showing a slightly modified form of the garment illustrated in Figs. 1, 2, and 3. Figs. 6 and 7 are detail plan views of the seat-piece 85 insertion employed in the garment shown in Figs. 2 and 4, respectively.

Referring first to Figs. 1, 2, 3, and 6, A designates the front and B the rear or back of the upper or body-portion of the garment; and C and D designate the front and rear, respectively, of the leg portions. The front A has a straight opening extending from the neck E to a point slightly above the crotch, the edges adjacent to such opening being suitably furnished with edging or binding and adapted to be separably united by buttoning over each other as shown at F; said edges being permanently united just above the front edge of the 100 crotch as by the transverse stitching indicated at G.

The garment herein shown is knit or woven in tubular form from top to bottom, the lower parts of the legs being formed by 105 splitting the tube centrally from the lower end to the crotch and then inseaming the edges of each leg by seams H to points a and b in the legs somewhat below the center of the crotch. 110

In carrying out my invention I extend the vertical split in the rear portion of the garment up to a point above the seat and preferably adjacent to or slightly above the 5 waist-line, such as the point indicated at *c* in Fig. 2; and to the edges formed by such vertical split I secure, as by sewing, the lateral outer edges of a pair of overlapping gore-pieces or gusset-inserts *I* and *K*, respectively, the former being shown in detail in Fig. 6, and the latter, in the garment shown in Figs. 1, 2, and 3, being of the same size and shape, but inversely disposed. As stated, the outer lateral margin *i* of the 10 insert *I* is secured to the edge of the corresponding rear side-body and leg portions of the garment by the seam *b*—*c* (Fig. 2). The lower edges *i'* and *i''* of the insert *I* are respectively secured to the edges of the front 15 side inseams of the legs from points *b* and *d* (Fig. 1) upwardly to the front median line of the garment along seams *b*—*e* and *d*—*e*, respectively. The other lateral edge *i³* of the insert *I* is free from a permanently attached point *f* slightly below the point *c* down to the point *d*.

The underlying insert *K* is secured in the rear body and upper leg or thigh portions of the garment in a similar manner, its 20 outer lateral edge (which corresponds with the edge *i* of the insert *I*) being secured to the edge of the corresponding rear side-body and leg portions of the garment by the seam *a*—*c* (Fig. 2); and the lower edges 25 thereof (corresponding to the edges *i'* and *i''* of the insert *I*) being secured to the edges of the front side inseams of the legs from the points *a* and *g* (Fig. 1) upwardly to the front median line of the garment 30 along seams *a*—*e* and *g*—*e*, respectively, which are partially coincident with the seams *d*—*e* and *b*—*e*, as clearly shown in Fig. 3. The other lateral edge *k³* of the 35 insert *K* is free from a permanently attached point *h* slightly below the point *c* down to the point *g*.

From the foregoing it will be seen that the outer insert *I* constitutes a seat-piece insertion, the lower angles of which form 40 in effect a pair of thigh-gore extensions; and it will be further noted that the lower portion of this seat-piece insertion forms a closed crotch, as most clearly shown in Fig. 1. In a measure the inner insert *K* (in the 45 form of garment shown in Figs. 1, 2, and 3) has the same functions as the outer insert *I*; but it also constitutes, in its relation to the body portion of the garment, a flap extension which underlies the free edge 50 of the seat-piece insertion *I* and co-operates with the latter in supplementing the size of the garment around the hips, its lower portion, which is extended and seamed into the inner portion of the leg, also forming 55

in effect a leg gore which supplements the size of the closed thigh portion of the leg.

The garment shown in Figs. 4, 5, and 7 is identical in principle of construction and manner of use with that above described, and shown in Figs. 1, 2, 3, and 6; the main 60 difference being that the outer gusset-insert or seat-piece insertion is somewhat wider and the lower angles thereof extend equally far down along the front side inseams of both legs, while the inner gusset-insert or 65 underlying flap extension is made narrower and extends into one leg only. The seat-piece insertion, in this form of the invention, is shown in detail at *M* in Fig. 7; one of its lateral edges *m* being joined to the 70 edge of the corresponding rear side-body and leg portions of the garment by the seam *b*—*c*; its lower edges *m'* and *m''* being secured to the front side inseams of the legs from the points *b'* and *a'* upwardly 75 to the front median line of the garment along the seams *b'*—*e'* and *a'*—*e'*, respectively (Fig. 5), and its other lateral edge *m³* being free from the permanently attached point *c'* down to the point *a'*. The 80 underlying flap extension *N* is joined at its longer lateral edge to the corresponding rear side-body and leg portions of the garment by a seam *a'*—*c'*; and its lower edge is secured to the front side inseam of one 85 leg coincidently with the seam *a'*—*e'* of the outer seat-piece insertion *M*. The other and shorter lateral edge *n³* of the flap extension *N* is free from the point *c'* down to and through the crotch to the point *e'*. In 90 this form of the invention the free edge *m³* of the outer seat-piece insertion *M* is preferably swelled slightly between its ends and provided with a button-hole *o* which may engage a button *p* sewed to the body-portion 95 of the garment.

In this form of the invention also the outer insert *M* constitutes a seat-piece insertion creating a permanently closed crotch, and the lower angles of which, extending 100 into the inner thigh portions of both legs, form thigh-gore extensions; while the insert *N* constitutes a flap extension underlying and co-operating with the seat-piece *M* in 105 supplementing the size of the garment around the hips; and its lower portion, running into the thigh portion of the leg, also forms a leg gore and supplements the size of the closed thigh portion of the leg.

I find in practice that the most satisfactory results in respect to the functions of the posterior opening of the garment are secured by running the free lateral edge of the seat-piece insertion down to a permanently attached point, such as *d* or *a'* at the inner 110 side of the leg below the crotch; and to prevent gaping of the garment resulting from 115 this formation, the underlying flap exten- 120 125

sion is quite essential, aside from the functions of the latter as a hip and thigh-gusset or gore to supplement the size of the garment in the hip and thigh regions.

5 I claim:

1. A bifurcated undergarment, having a permanently closed crotch formed by a seat-piece insertion having its lower angles formed into a pair of thigh-gore extensions 10 respectively seamed to the edges of the front side inseams of the legs from the points of said extensions upwardly to the front median line of the garment, one of the lateral edges of said seat-piece being joined to the 15 edge of the corresponding rear side-body and leg portions of the garment from the point of the thigh-gore extension to a point above the seat, the other lateral edge of said seat-piece left free from a permanently attached point below the crotch substantially 20 at the inseam of the opposite leg to a point above the seat; and a flap extension secured to the edge of the other rear side-body lapsing the free edge of said seat-piece and co- 25 operating with the latter in supplementing the size of the garment around the hips.
2. A bifurcated undergarment, having a permanently closed crotch formed by a seat-piece insertion having its lower angles 30 formed into a pair of thigh-gore extensions respectively seamed to the edges of the front side inseams of the legs from the points of said extensions upwardly to the front median line of the garment, one of the lateral 35 edges of said seat-piece being joined to the edge of the corresponding rear side-body and leg portions of the garment from the point of the thigh-gore extension to a point above the seat, the other lateral edge of said 40 seat-piece left free from a permanently attached point below the crotch at the inner side of the opposite leg to a point above the seat; and a flap extension secured to the

edge of the other rear side-body and lapsing the free edge of said seat-piece, the 45 lower end portion of said flap extension being extended and seamed into the leg and forming a leg gore, whereby the major portion of the flap supplements the size of the garment around the hips and the lower portion thereof supplements the size of the 50 closed thigh portion of the leg.

3. A bifurcated garment, having a permanently closed crotch and flap-covered opening extending from a point above the seat to 55 a point at or near the inseam of one leg and below the crotch, comprising in combination with the body and legs, a seat-piece having its lower portions formed into thigh extensions for the respective legs, each thigh extension being seamed along the leg inseam from the lower extremity of the extension to the middle of the crotch, one of the lateral outer edges of said seat-piece being joined to the edge of the corresponding rear side- 60 body from the lower extremity of the thigh-extension to a point above the seat, the opposite lateral outer edge of said seat-piece being left free to open from said point substantially at the inseam of the corresponding 65 leg and below the crotch to a point above the seat.

4. A union garment having a substantially continuous seam forming the legs and crotch and a normally closed up and down 70 posterior opening formed by inner and outerlapping members with free edges extending from permanent connections above the seat to permanent connections below the crotch, said members having free edges terminating 75 and fixed substantially at said seam.
